CHRISTOPHER A. SCHELLENS, OF MARBLEHEAD, MASSACHUSETTS, ASSIGNOR TO C-S ENGINEERING COMPANY, OF JERSEY CITY, NEW JERSEY, A CORPORATION OF DELAWARE

TENDER FEED WATER HEATER

Application filed June 20, 1926. Serial No. 119,630.

This invention relates to locomotive feed water heaters and has for its primary object the provision of simple and effective means for heating the feed water, particularly designed to meet certain operating difficulties which arise in service.

Another object of the invention is to provide a combination of feed water heating devices calculated to meet conditions which arise by virtue of physical limitations as to size as will further appear.

A more specific object of the invention is to supplement the primary heater, which is usually placed somewhere on the locomotive and in this instance is located at the front end, by means of a simple feed water heater located in the tender of the locomotive.

A further object of the invention is to provide heating means which may be located to advantage in the tender.

How the foregoing together with such other objects and advantages as may herein-after appear or are incident to my invention, are realized, is illustrated in preferred form in the accompanying drawings, wherein

Fig. 1 is a diagrammatic broken-out side view of a locomotive with a fragment of the tender shown in section and with my invention shown applied thereto;

Fig. 2 is an enlarged longitudinal section thru the tender feed water heater which I employ; and

Fig. 3 is a plan section taken on the line 3—3 of Fig. 2.

Although feed water heaters of the usual type are provided with heating surfaces which are ample when the heater is clean it is pointed out that in service the heater becomes covered with dirt and oil which greatly impairs its effectiveness. The natural thought therefore would be to increase the amount of heating surface to the point where the heater would be efficient even when dirty, but this is objectionable due to physical limitations as to size of the heater, with which those skilled in the art are familiar. I aim to offset the loss incident to the accumulation of dirt in the usual heater by providing a simple heater located in the tender which

is adapted to supplement the main heater, which has the same effect as increasing the heating surface of the main heater, in that the tender heater provides a reserve heating capacity which is especially useful when the main heater becomes covered with dirt. By this arrangement the highest temperatures of the feed water are obtained.

Referring now more particularly to Fig. 1 it will be seen that I have therein indicated a locomotive 4 carrying at its forward end 5 a feed water heater 6 which is supplied with steam, preferably exhaust steam from the main cylinders of the locomotive, thru the medium of the pipe or pipes 7. Exhaust steam from other appliances of the locomotive, such for example as the air pump, may also be admitted to the heater thru the pipe 8. Water is supplied to the heater in a manner to be hereinafter described, and the heated water is led from the heater 6 to the locomotive boiler by means of the pipe 9 and the boiler check 10.

The exhaust steam and condensate of the heater 6 is led backwardly to the tender feed water heater 11 by means of the pipe line 12, a check valve 13 being provided in this pipe line to prevent the water in the tender from flowing into the line.

Referring now to Figs. 2 and 3 the tender feed water heater 11 comprises a casing 14, preferably of cylindrical form, having an annular steam chamber 15 at its lower portion with which the pipe line 12 communicates and a pump suction or water withdrawal orifice 16 thru which water is drawn from the tender.

The heater 11 is preferably located in the lower forward portion of the tender, the casing 14 thereof being spaced somewhat from the bottom of the tender so as to provide the space or restricted passageway 17 thereunder, thru which the water to be heated is passed as will further appear.

A plurality of holes 18 are provided in the bottom of the steam chamber 15 thru which the steam discharges for the purpose of heating the water passing from the tender to the orifice 16.

A removable strainer 19 is provided around

the orifice 16 for the purpose of preventing any large pieces of coal or other matter from passing into the pipe line 20. This strainer also, in a measure serves to deflect the water current upward so that bubbles of air will be less likely to be drawn through the feed water pump 21 which pump is located in the water line 20.

10 A tank valve 20a for controlling the water leaving the tender is located at any convenient point in the pipe line 20 and in this instance I have shown it located at the suction end of the pipe line 20. This valve is shown in its closed position in Fig. 2.

15 The operation of the device is as follows. The exhaust steam together with the condensate of the main heater 6 passes thru the pipe line 12 to the steam chamber 15 of the tender heater 11 from which it discharges thru the holes 18 into the water passing thru the passageway 17. Water is drawn from the tender, thru the passageway 17 to the suction orifice 16 and into the water line 20 by means of the pump 21, from which it is delivered to the main heater 6. Thus it will be seen that the water passes directly across the steam issuing from the steam ring of the heater and is consequently heated by said steam. It is to be observed that by this arrangement the water being drawn by the pump is heated without imparting a sensible amount of its heat to the remaining water in the tender. In this connection it is pointed out that the casing 14, which has an open bottom, surrounds the orifice 16 thus serving the purpose of preventing currents of hot water which escape the suction from the orifice from rising and mixing with the body of water in the tender. The tender heater also acts to deaerate the water before it enters the pump, an effect which is especially desirable in view of the fact that corrosion in the boiler is accelerated when there is air in solution in the feed water supplied to the boiler.

20 The tank valve 20a as here shown has an actuating rod 20b extending upwardly thru an enclosing tube 22 and is provided with a handle 23 whereby it may be manipulated by the engineman. The tube 22 is secured in any suitable manner to the heater casing 14 and is of such diameter as to permit the valve to be drawn therethrough. This tube terminates a little short of the top of the tender for the purpose of permitting any gas which may enter with the steam to rise and pass out at the top thereof.

25 In the preferred arrangement of my invention I combine this tender heater device with the usual heater indicated at 6 and in this combination the water is first warmed in the tender heater and then pumped directly into the usual heater. It is of course evident that this tender heating device can be used however, without the other or so

called usual heater in which case low pressure steam is to be taken directly from the cylinders and the water pumped directly to the check valves.

30 A further advantage of this arrangement of apparatus is that when both heaters are used together it does away with the necessity for a steam trap and the heating in a closed heater is improved by the rapid circulation of steam thru it, which steam passes directly into the tender heater. If this condensate and steam were to be blown directly into the suction line it is evident that when the pump stops, the suction line would become filled with steam and non-condensable gases and upon starting it would be found to be steam bound.

35 From the foregoing it will be seen that in general the tender heater may be described as an arrangement for heating feed water in a locomotive wherein exhaust steam or a mixture of exhaust steam and condensate is led to the tender in a manner to heat the water locally and whereby this heated water is drawn off without sensibly dissipating heat to the body of water in the tender.

40 I claim:—

1. The combination with a locomotive tender and its water withdrawal orifice of a heater casing associated with the orifice and adapted to segregate that portion of the water in the immediate zone of the orifice from the remainder of the water in the tender, and means for discharging through said casing a heating medium into direct contact with the water as it passes to said zone for discharge through the withdrawal orifice.

45 2. The combination with a locomotive tender and its water withdrawal orifice of a heater casing associated with the orifice spaced somewhat above the floor of the tender to provide a restricted passage thru which water must flow from the tender to the orifice, and means for introducing a heating medium into said heater casing, said heater casing having means for directing the heating medium into the water passing through said passageway.

50 3. The combination with a locomotive tender and its water withdrawal orifice of a heater casing associated with the orifice spaced somewhat above the floor of the tender and having an open bottom, said casing having a steam ring arranged concentrically with the water withdrawal orifice and said steam ring discharging its steam into the water passing to the withdrawal orifice through the aforesaid space.

55 4. A locomotive feed water heater for tenders having a water withdrawal orifice, and a heating chamber mounted to surround said orifice and produce local heating of the feed water in its passage from the tender to said orifice, said heating chamber having an inlet for a heating medium and an outlet

for discharging the heating medium directly into the water passing to said orifice.

5. A locomotive feed water heater for tenders having a water withdrawal orifice, and a heating chamber spaced above the floor of the tender for producing local heating of the feed water in its passage from the tender to said orifice, the local heater having outlets for the discharge of the heating medium directly into the water and said heater being annularly disposed around the orifice.

10. A locomotive feed water heater for tenders comprising an inlet for admitting exhaust steam and condensate to the tender and a suction outlet for withdrawing water from the tender, said inlet and outlet being so disposed relative to one another that the water heated by the steam is withdrawn without sensibly dissipating heat to the remaining body of water in the tender, together with a vent whereby non-condensable gases and excess steam may escape.

15. A locomotive feed water heater for tenders having a water withdrawal orifice, comprising a heating device in the form of a hood within the tender and spaced above said orifice, and means for discharging a heating medium into the space between the orifice and hood, said heating medium being entrained with the water as the water passes through said space to the water withdrawal orifice.

20. A locomotive feed water heater for tenders having a water withdrawal orifice, comprising a heating device in the form of a hood within the tender and spaced above said orifice, and means for discharging a heating medium into the space between the orifice and hood, said heating medium being entrained with the water as the water passes through said space to the water withdrawal orifice, together with a vent for said hood.

25. A locomotive feed water heater for tenders having a water withdrawal orifice, comprising a heating device located in close proximity to the orifice and having means for discharging its heating medium into the water substantially at the withdrawal orifice whereby said heating medium is entrained with the water passing to the orifice.

30. The combination of a locomotive feed water heater for tenders having a water withdrawal orifice, comprising a chamber within the tender having steam inlet and outlet, said chamber being so located with respect to the withdrawal orifice that steam discharging from the chamber contacts with water passing to the orifice, a vent associated with said chamber for the escape of air present as an incident to operation; a steam heated feed water heater outside of said tender, and a connection between said outside heater and the aforesaid steam inlet whereby exhaust steam from the outside heater is supplied as the heating medium for the inside heater.

35. 11. The combination of a locomotive feed water heater for tenders having a water withdrawal orifice, comprising an open bottomed annular casing located over said orifice and concentric therewith, an annular chamber in said casing having a steam inlet and a plurality of annularly arranged steam outlets for discharging steam into the water passing to the withdrawal orifice, a vent for the escape of air from said casing; a steam heated feed water heater outside of the tender; and a connection between said outside heater and the aforesaid steam inlet whereby exhaust steam from the outside heater is supplied as the heating medium for the inside heater.

40. 12. The combination with a locomotive tender and its feed water outlet, of means for drawing water through the outlet, and means employing steam for heating the water being drawn only at a point immediately adjacent the outlet, by direct contact with the steam, and including a shallow vented dome in alignment with the outlet and spaced slightly above the floor of the tender to provide water flow space to the outlet.

45. 13. In combination with a locomotive and its tender provided with a feed water outlet, a main feed water heater on the locomotive, means for supplying steam to such heater, a heater within the tender and segregating a portion of the water therein adjacent the outlet, a pipe leading from the main heater to the heater in the tender and serving as an exhaust steam outlet and drain for the former and steam supply pipe for the latter, and a vent for the heater in the tender, whereby the main heater vents through the tender heater.

50. 14. In combination with a tender and its water outlet, a feed water heater device including a relatively small chamber communicating with said outlet, open at the bottom and spaced slightly from the tender bottom, a vent-pipe extending from said chamber to a point above the tender water level, and means for discharging a heating medium into the water adjacent the lower peripheral edge of said chamber.

55. In testimony whereof, I have hereunto signed my name.

CHRISTOPHER A. SCHELLENS.
